DESIGN.

—o—
T. HILL,

MUSICAL INSTRUMENT CASE.

No. 17,625.

Patented Aug. 9, 1887.

UNITED STATES PATENT OFFICE.

THOMAS HILL, OF CHICAGO, ILLINOIS, ASSIGNOR TO STORY & CLARK, OF SAME PLACE.

DESIGN FOR A MUSICAL-INSTRUMENT CASE.

SPECIFICATION forming part of Design No. 17,625, dated August 9, 1887.

Application filed June 23, 1887. Serial No. 242,329. Term of patent 7 years.

To all whom it may concern:

Be it known that I, THOMAS HILL, a subject of the Queen of Great Britain, residing at Chicago, county of Cook, and State of Illinois, have invented and produced a new and original Design for Musical-Instrument Cases, of which the following is a specification, reference being had to the accompanying drawing, forming a part thereof.

- 10 o The figure in the drawing is a perspective view from the front corner of an organ-case embodying my design.

My design embraces two portions of an organ-case—the upper part an ornamental cabinet top and the lower part an organ-case proper. The former is composed of three parts—the central hooded recess, A, backed by a mirror, and the side cases, B B, forming the sides of the alcove and lower than it, having paneled fronts and surmounting slender turned legs b b b b. The lower part or organ-case proper has at each end the pilasters E E, each of which is of the same width from base to capital, and formed of the molded pedestal E', round beaded shaft E², and capital E³, supporting the entablature F, which comprises the architrave f, frieze f', whose front side is J-shaped, as shown, and cornice f². The front corners of the case are formed of the pilasters D D, each of which is composed of the pedestal d, fluted column d', and capital d², supporting the entablature F, the effect of solidity and massiveness produced by these four end and two corner pilasters being the principal feature of this portion of my design.

15 The detail design of the corner pilaster is as follows: The pedestal retreats from its base obliquely upward to the lower base of the column, forming a short horizontal step and half-round mold on the way up. The base of the column is a half-round mold below a half-round cove. The shaft is round and beaded and ends in an ogee and reeds above. The capital, comprising more than half the whole 20 length of the column, has two rectangular facets, d²⁰ and d²¹, and a deep three-quarter-round cove, d²², intervening. Above the upper facet a series of swells leads to the bold knee d²³, which forms the front upper corner

of the capital, and is one of the most prominent features of this portion of the design. The end pilasters have substantially the same general outline as to their pedestals and columns. Their capitals are of the same length as those of the front pilasters, and above the columns have a rectangular facet, above which is a half-round mold, next a long shallow cove, above which is a prominent swell, E², and above it another long shallow cove similar to the one below, leading to a series of half and three-quarter round molds, in which the capital ends.

25 I claim—

1. The design for a musical-instrument case herein described and set forth, comprising end and corner pilasters whose shafts are round and whose capitals are more than half the length of the entire pilasters, and entablature surmounted by an ornamental top resting upon slender corner legs, and having a mirror set in a central hooded recess between side panels shorter than the mirror, the capitals of the end pilasters having each a prominent central swell between two long shallow coves, the capitals of the corner pilasters having each a deep three-quarter-round cove between rectangular facets and flowing curves above the upper facet extending to the knee, which forms its upper front corner.

2. In a design for a musical-instrument case, the ornamental top herein described and shown, comprising a mirror set in a central hooded recess between ornamental side panels shorter than the mirror, the whole resting upon slender corner legs.

3. The design for a musical-instrument case herein described and shown, comprising the entablature F, consisting of the architrave f, the frieze f', and cornice f², supported by the pilasters E E against the ends and corner pilasters D against the front, the corner pilasters comprising pedestals having rectangular facets at the base and retreating obliquely upward by a horizontal step and half-round mold and oblique facet, columns whose bases are half-round molds below half-round coves, whose shafts are fluted and end in ogees and reeds, capitals forming more than half the length of the pilasters, and which have two rectangular

facets, one above and one below a deep three-quarter-round cove, and which extends upward from the upper facet in flowing curves to the knee and then rearward and upward to 5 the entablature, the end pilasters being similar in design as to their pedestals, and columns to the corner pilasters, their capitals being of the same length, but having above the columns rectangular facets, above which are half-round 10 molds, next long shallow coves, above which are prominent swells, and above them long shallow coves similar to the ones below, leading to a series of half and three-quarter round molds, in which the capitals end.

15 4. In a design for a musical-instrument case, the pilaster herein described and shown, comprising pedestals having rectangular facets at

the base and retreating obliquely upward by a horizontal step and half-round mold and oblique facet, columns whose bases are half-round 20 molds below half-round coves whose shafts are fluted and end in ogees and reeds, capitals forming more than half the height of the pilasters, and which have two rectangular facets, one above and one below a deep three-quarter-round cove, and which extends upward from the upper facet in flowing curves to the knee and then rearward and upward to the entablature. 25

THOMAS HILL.
